US00D855402S

(12) **United States Design Patent** (10) **Patent No.:** **US D855,402 S**
Steinmann (45) **Date of Patent:** **** Aug. 6, 2019**

(54) **PORTABLE BEVERAGE CONTAINER**(71) Applicant: **Hydrovaze LLC**, Laguna Niguel, CA (US)(72) Inventor: **Hardy Steinmann**, Laguna Niguel, CA (US)(73) Assignee: **Hydrovaze LLC**, Laguna Niguel, CA (US)(**) Term: **15 Years**(21) Appl. No.: **29/635,219**(22) Filed: **Jan. 29, 2018****Related U.S. Application Data**

(63) Continuation of application No. 29/563,456, filed on May 4, 2016, now Pat. No. Des. 815,901.

(51) **LOC (12) Cl.** **07-01**
(52) **U.S. Cl.**USPC ..... **D7/510**; D7/511; D7/523(58) **Field of Classification Search**

CLAIM

I claim the ornamental design for a portable beverage container, as shown and described.

DESCRIPTION

FIG. 1 is a top front perspective view of a portable beverage container showing my new design;

FIG. 2 is a front perspective view of the portable beverage container shown in FIG. 1;

FIG. 3 is a rear perspective view of the portable beverage container shown in FIG. 1;

FIG. 4 is a left side view of the portable beverage container shown in FIG. 1;

FIG. 5 is a right side view of the portable beverage container shown in FIG. 1;

FIG. 6 is a top view of the portable beverage container shown in FIG. 1; and,

FIG. 7 is a bottom view of the portable beverage container shown in FIG. 1.

The broken lines in the drawings depict portions of the portable beverage container that form no part of the claimed design.
